SOUND EMITTING DOLL SUPPORTING TOY

David Sebel, London, England, assignor to D. Sebel and Company Limited, Erith, England, a British company

Application June 5, 1951, Serial No. 229,909

Claims priority, application Great Britain
January 31, 1951

6 Claims. (Cl. 46—175)

The present invention relates to toys more particularly toys adapted to removably support a doll or like toy figure and has for an object to provide an improved construction of such toys whereby a sound emitting device adapted to be mounted on the toy and simulating the voice of the doll or like toy figure is actuated by a mechanism operable at will by the user of the toy.

Broadly the invention comprises in a toy of the type specified the provision of a sound emitting device and operating mechanism therefor, a manually operated actuating device for said mechanism, and means operatively connecting said device to the mechanism whereby operation of the said device effects actuation of the mechanism and operation of the sound emitting device.

The connecting means may take the form of a mechanical connection such as for example a link mechanism, a cord and pulley arrangement, or a Bowden cable. It may also comprise pneumatic or electromagnetic means. The actuating device may be mounted upon any convenient part of the toy such as for example the handle of a push chair or the base of a doll's chair or cradle; or it may be connected thereto by flexible means such as for example a Bowden cable, electric cable or pneumatic tubing.

Conveniently the sound emitting device may comprise a weight loaded bellows of the type known as a "crier" in which rotation of the bellows about a horizontal axis transversely thereof causes an intermittent sound to be emitted which sound may be made to simulate the human voice.

The invention may be incorporated into the construction of a toy such as for example a push chair, perambulator, a cradle or bed, or a doll's chair; or it may comprise a separate unit adapted to be attached to such toys.

The invention will now be described with reference to the accompanying drawings showing various embodiments thereof. In the drawings:

Figure 1 is a side elevation of a push chair according to the invention, the near side wheels being omitted to show details of construction;

Figure 2 is a front elevation thereof;

Figure 3 is a section taken along the line III—III of Figure 2 and drawn to an enlarged scale;

Figure 4 is a section taken along the line IV—IV of Figure 3;

Figure 4a is a partial sectional view similar to Figure 4 and showing an alternative construction;

Figure 5 is a sectional elevation of a modified construction of the actuating mechanism;

Figure 6 is a rear view, with the back plate removed, of a unit for attachment to a toy;

Figure 7 is a section taken along the line VII—VII of Figure 6;

Figure 8 is a diagrammatic representation of a further modified construction of the actuating mechanism adapted for electrical operation;

2

Figure 9 is a partial sectional view similar to Figure 4 and showing a still further modification;

Figure 10 is a side elevation of a doll's chair according to the invention; and

Figure 11 is a front elevation thereof, one of the front legs being omitted and the corresponding rear leg shown partly in section to illustrate details of construction.

Referring to Figures 1 and 2 of the drawings, a push chair according to the invention comprises a seat 1 and a foot rest 2 supported on a pair of side frames 3, formed of lengths of tubular metal, which are in turn supported upon wheels 4 rotatably mounted thereon by spindles 5. A handle indicated generally at 6 of substantially inverted U shape supports a hollow back rest 7 which is secured thereto as by welding for example, the legs of the handle being secured in sleeves 8 secured to the side frames 3. The spindles 5 are screw threaded to receive nuts 9 whereby the spindles serve to secure the footrest 2 and the sleeves 8 to the side frames. The sleeves are formed at their upper ends with projections 10 adapted to engage in apertures 11 in the walls of the tubular side frames thus positioning the handle with respect to the frames.

A crier 12 (Figure 3) is mounted within the hollow back rest 7 and is actuated by a member 13 pivotally mounted upon the handle by means of a pin 14 and operatively connected to the crier in a manner to be hereinafter described whereby rocking of the member 13 about its pivot effects actuation of the crier.

Referring now more specifically to Figures 3 and 4, the hollow back rest 7 comprises a cover 15 secured to a base 16 joined along its side edges as by welding for example to tubular members 17 forming the legs of the handle 6. Pivotally mounted upon the base 16 by means of a stud 18 is a member 19 having at its upper end an arcuate rack 20. The rack 20 engages a pinion 21 secured to a spindle 22 journaled at one end in a boss 23 formed in the base 16, and having secured thereto at its other end the crier 12.

Thus rocking of the member 19 about its pivot 18 rotates the pinion 21 and spindle 22 by means of the rack 20 thereby rotating the crier 12 and causing a sound to be emitted. Apertures 24 are provided in the base 16 to enable the sound emitted by the crier to be clearly heard.

Rocking of the member 19 is effected by means of a link 25 having at one end a pin 26 secured thereto which pin engages in a slot in the member 19. The bar 25 is pivotally connected at its other end to one arm of a bell crank lever 28 pivoted as at 29 upon the base 19. The other arm of the bell crank lever extends through an aperture 30 in the cover 15 and is adapted to receive one end of a rod 31 extending upwardly through the tubular member 17, the rod being bent as at 32 to pass through an aperture 33 in the bell crank lever.

The upper end 34 of the rod 31 is pivotally attached as at 34a to the member 13 adjacent the end thereof, said member being of hollow box like form adapted to cover and enclose the upper ends of the tubular members 17 and being pivotally mounted by means of the pin 14 upon a channel section stretcher 35 extending between the tubular members 17 and secured thereto at its ends as by welding for example.

The member 13 is spring loaded by means of a compression spring interposed between the member and the stretcher 35 and it will be apparent that rocking motion of the member 13 about its pivot will be transmitted by the rod 31 and bell crank lever 28 to the link 25 thereby causing the link to move first in one direction and then in the other transversely of the base 16 to effect rocking

of the member 19 which by reason of the rack 20 and pinion 21 causes rotation of the crier 12.

In an alternative construction shown in Figure 4a, the rod 31 and bell crank lever 28 are respectively replaced by a flexible cord or wire 36 and grooved pulleys 37 and 38. The pulley 37 is mounted upon a spindle 39 extending diametrically across the sleeve 8, the diameter of the pulley being such as to permit the cord 36 to pass freely through the tubular member 17. The cord 36 is secured at its upper end to the handle member 13 (not shown) and after passing over the pulley 37 passes through an aperture 40 in the back rest cover 15, over the pulley 38 rotatably mounted upon the base 16, and is secured to the end of the link 25. The cord or wire 36 is tightly tensioned and may if desired include tensioning means such as for example a helical spring. It will be apparent that rocking of the member 13 alternatively effects a pull on the cord 36 thereby causing oscillatory movement of the link 25 which in this modified construction is spring loaded as at 25a.

Figure 5 is a sectional elevation of a back rest embodying a modification of the actuating mechanism of Figures 3 and 4.

In the construction shown in Figure 5 a crank member 41 journaled at its lower end in a boss 42 formed in the base 16 and adapted to be rocked about its lower end, is bent at its upper end as at 43 to engage in a slot 44 in an arm 45 pivoted at its lower end as at 46 to a supporting bracket 47 secured to the base 16. The arm 45 supports at its upper end the crier 12 secured thereto by means of a clamp 48 so that the longitudinal axis of the crier lies substantially at right angles to that of the arm. The length of the arm 45 and the slot 44, and the position of the pivot 46 are made such that when the crank member is at one extreme angular position, the arm 45 occupies a substantially horizontal position, and movement of the crank member to its other extreme angular position rotates the arm 45 through 180° thereby inverting the crier and effecting operation thereof.

Rocking of the crank member 41 is effected by a transverse bar 49 journaled intermediate its length upon the crank member and connected at its ends to the bell crank levers 28 which levers are actuated, as in the construction shown in Figures 3 and 4 by rods passing through the tubular members 17. Alternatively the bar 49 may be actuated by a cord and pulley arrangement similar to that shown in Figure 4a.

Referring now to Figures 6 and 7, a unit adapted to be attached to a toy comprises a base 50 and a cover 51 secured thereto. A crier 52 is secured upon one end of a spindle 53 by means of a support 54, the other end of the spindle being journaled in a boss 55 formed in the cover 51, the said spindle having mounted thereon a pinion 56. The pinion 56 is adapted to engage a rack 57 formed on a transversely extending member 58 slidably supported in brackets 59 secured to the cover 51 whereby oscillatory movement of the member 58 causes oscillation of the spindle 53 about its axis and actuation of the crier 52.

The member 58 is spring loaded in one direction by a spring 60 secured to one end thereof and to the cover 51 and has connected at its other end the wire 61 of a Bowden cable 62 secured to the cover as at 63 and provided at its free end with a suitable operating device (not shown) such as for example the known type of hand grip.

Thus repeated operation of the Bowden cable operating device effects movement of the member 58 first in one direction and then in the other thereby imparting oscillatory movement to the spindle 53 and actuation of the crier.

Spring clips 64 are secured to the base 50 and serve for detachably securing the unit to a toy. Other suitable attachment means such as for example suction pads may be employed, or the unit may be adapted to be secured

by screws or nuts and bolts when it is intended as a permanent attachment to an existing toy.

In the further modified construction diagrammatically shown in Figure 8, operation of the crier actuating mechanism is effected by electro magnetic means. In this construction the pivoted member 19 of Figures 3 and 4 is rocked from side to side by means of a transverse member 65 slidably supported in a bracket 66 and pivotally secured at one end to the member 19. The other end of the transverse member is formed with a stop 67 adapted to be engaged by one arm of a bell crank lever 68. The other arm of the bell crank lever is slotted as at 69 to receive one end of a plunger 70 of magnetic material and slidably supported at its other end in a solenoid 71.

By alternately energising the solenoid, the bell crank lever 68 is rocked about its pivot by the plunger 70 thereby imparting oscillatory motion to the transverse member 65 to cause rocking of the pivoted member 19 and actuation of the crier, the member 19 being spring loaded by a spring 72 against the pull exerted by energisation of the solenoid 71.

The electric power for energising the solenoid 71 is supplied by a battery shown diagrammatically at 73 which battery may be conveniently accommodated in the toy as for instance beneath the seat of the push chair shown in Figures 1 and 2. A switch 74 is connected by means of wires 75 to the solenoid and to the battery and it will be appreciated that intermittent operation of the switch will cause the solenoid to be intermittently energised thus oscillating the transverse member 65 and thereby rocking the pivoted member 19 to effect actuation of the crier in the manner hereinbefore described with reference to Figures 3 and 4.

Figure 9 shows a still further modified construction 35 of the mechanism shown in Figures 3 and 4. In the modified construction shown in Figure 9 the pivoted member 19 is actuated by pneumatic means. To this end a piston rod 76 of an air operated piston 77 sliding in a cylinder 78 is connected to the member 19 by means of a link 79 having a pin 80 sliding in a slot in the member 19. The member is spring loaded in one direction by a spring 82 secured thereto and to a bracket 83 secured upon the base 16, movement of the member 19 in the other direction being effected by outward movement of the piston 77. The cylinder 78 is connected by means of a flexible tube 84, passing through an aperture in the back rest cover 15 and a slot 86 in the tubular member 17 and extending upwardly therethrough to connect with a bellows 87 interposed between one end of a pivoted handle member 88 and the upper end of the tubular members. The bellows 87 is spring loaded to the extended position, the handle member 88 being pivoted on a pair of upstanding lugs 89 formed upon a flat bracing member 90 uniting the upper ends of the tubular members 17. It will be apparent that rocking of the member 88 about its pivot will cause the bellows 87 to be alternately contracted and extended thereby alternately forcing air into the cylinder 78 and evacuating it therefrom to effect oscillatory movement of the piston 77. The member 19 is thereby rocked about its pivot by the piston rod 76 and link 79 to effect actuation of the crier in the manner hereinbefore described.

Operation of the piston 77 may be effected by means other than the bellows 87. For example the tube 84 65 may be connected to a deflatable rubber globe adapted to be secured to any convenient part of the toy or connected thereto by tubing so that the toy may be operated from a position remote therefrom.

Alternatively the handle member 88 and bracing member 90 may be replaced by a tubular handle member having at one end thereof an air chamber formed of rubber tube and constituting part of the handle member. The flexible tubing 84 is connected to the said air chamber and it will be apparent that pressure upon the rubber tube portion of the handle member by the hand of the

user of the toy will effect operation of the piston 77 and actuation of the crier.

Figures 10 and 11 show a further embodiment of the invention in which a doll's chair is provided with means for actuating a sound emitting device or "crier" mounted thereon.

As will be seen from the figures, a doll's chair comprises a pair of side frames indicated generally at 91, of metal tube bent to the desired shape to provide leg portions 92 and horizontal seat supporting portions 93. The leg portions of each side member are connected by stretcher members 94 and the frames are connected in spaced parallel relation by a front stretcher 95 and a rear stretcher 96. A seat 97 is supported from the frame portions 93 by brackets 98 which embrace the said portions and are secured thereto as by rivets 99.

A hollow back rest 100 is supported upon a base 101 extending downwardly therefrom and secured along its side edges as by welding for example, to the rear leg portions 92 of the side frames 91. A crier is mounted within the back rest 100 upon the base 101 which base also supports the crier actuating mechanism shown in Figures 3 and 4, the said mechanism being operated in the case of the construction shown in Figures 10 and 11, by a bell crank lever 102 pivoted on the base 101, one arm of the said lever extending through an aperture 103 in the rear leg member. The said arm is connected by means of a downwardly extending rod 104 to a projection 105 formed at one end of a rockable member 106 which projection extends through a further aperture 107 in the rear leg member.

The rockable member 106 is pivoted upon the rear stretcher 96 and is spring loaded in the anticlockwise direction as viewed in Figure 11 so that foot operation of the said member by intermittent pressure of the foot of the user of the toy upon the end of the member adjacent the projection 105 effects rocking of the bell crank lever 102 and actuation of the crier operating mechanism.

It will be appreciated that instead of the construction described with reference to Figures 10 and 11, any of the constructions shown in Figure 4a, 5, 6, 7, 8 or 9 may be incorporated into the doll's chair and, in the case of the constructions shown in Figures 6, 7, 8 and 9, remote controlled operating means may be provided for operating the toy at a distance.

It will likewise be understood that the invention is not limited to the above described embodiments thereof and that it is applicable to toys other than those shown in the drawings such as for example a doll's cradle or bed; or in fact any toy adapted to removably support a doll or like toy figure.

What I claim is:

1. In a toy push chair comprising a back rest and a handle mounted on a framework supported on wheels, the combination with said back rest, of a sound emitting device capable of emitting sound upon a predetermined movement of said device, said device being supported on said back rest for said predetermined movement thereof relative to said back rest, a manually operable member mounted on said handle for movement thereof relative to said handle, and means operatively connecting said member to said sound emitting device to produce said predetermined movement of said device upon said movement of said manually operable member relative to said handle.

2. In a toy push chair the combination as defined in claim 1 in which said means operatively connecting said manually operable member to said sound emitting device comprises a rod and link mechanism operatively connected between said member and said device.

3. In a toy push chair the combination as defined in

claim 1, in which said sound emitting device is rotatably supported by said back rest, said device being capable of emitting sound upon such rotation thereof, said means operatively connecting said manually operable member to said sound emitting device comprising a driving member supported by said back rest for rotation thereof and operatively connected to said sound emitting device for effecting rotation of said device upon rotation of said driving member, a transmission member supported by said back rest for movement of said transmission member relative to said back rest and operatively connected to said driving member for effecting rotational movement of said driving member and of said sound emitting device upon said movement of said transmission member, said manually operable member being operatively connected to said transmission member for effecting said movement of said transmission member upon operation of said manually operable member to produce sound emitting rotational movement of said sound emitting device.

4. In a toy push chair the combination as defined in claim 1, in which said means operatively connecting said member to said sound emitting device comprises a spindle supported by said back rest for rotation thereof on the spindle axis, said sound emitting device being carried by said spindle for rotational movement thereof with the spindle on its axis, said device being capable of emitting sound upon such rotational movement thereof, a pinion secured to said spindle for rotation therewith, a transmission member providing gear teeth engaging the teeth of said pinion and supported on said back rest for reciprocating movement of said transmission member to produce reciprocating movement of said pinion and said spindle upon such reciprocating movement of said transmission member, and means operatively connecting said manually operable member to said transmission member for effecting said reciprocating movement of said transmission member upon operation of said manually operable member.

5. In a toy push chair the combination as defined in claim 4, in which said transmission member is a quadrant pivotally supported on said back rest and provided with gear teeth engaging the teeth of said pinion to produce reciprocating rotation of said pinion and said spindle upon the reciprocating movement of said quadrant, said manually operable member being operatively connected to said quadrant to effect said reciprocating movement of said quadrant upon operation of said manually operable member.

6. In a toy chair comprising a back rest mounted on a framework adapted to rest upon a floor or like surface, the combination with said back rest, of a sound emitting device capable of emitting sound upon a predetermined movement of said device, said device being supported on said back rest for said predetermined movement thereof relative to said back rest, a member operable at will supported on said framework adjacent said floor or like surface for movement thereof relative to said framework, and means operatively connecting said member to said sound emitting device to produce said predetermined movement of said device upon said movement of said member operable at will.
